(57) **CLAIM**

The ornamental design for a beverage cooling system, as
shown and described.

DESCRIPTION

FIG. 1 is a perspective view of a beverage cooling system
according to the present invention including a beverage cooling
device being carried by a beverage cooling container.

FIG. 2 is an exploded perspective view of the beverage cooling
system illustrated in FIG. 1 showing the beverage cooling
device being removed from the beverage cooling container.
FIG. 3 is a side elevation view of the beverage cooling
container of the beverage cooling system illustrated in FIG. 1.
FIG. 4 is a top plan view of the beverage cooling container
illustrated in FIG. 3.

FIG. 5 is a bottom plan view of the beverage cooling container
illustrated in FIG. 3.

FIG. 6 is a perspective view of a beverage cooling device
of the beverage cooling system illustrated in FIG. 1.

FIG. 7 is a front elevation view of the beverage cooling device
illustrated in FIG. 6; and,

FIG. 8 is a side elevation view of the beverage cooling device
illustrated in FIG. 6.

The beverage cooling container and device are shown separately
for clarity of illustration.
